THOMAS S. GREENMAN, OF MYSTIC BRIDGE, ASSIGNOR TO GEORGE W. PACKER, JR., OF MYSTIC RIVER, CONNECTICUT.

Letters Patent No. 72,024, dated December 10, 1867.

IMPROVED MACHINE FOR WALL-BUILDING AND STUMP-EXTRACTING.

The Schedule referred to in these Letters Patent and making part of the same.

TO ALL WHOM IT MAY CONCERN:

Be it known that I, THOMAS S. GREENMAN, of Mystic Bridge, in the town of Stonington, county of New London, and State of Connecticut, have invented certain new and useful Improvements in Machines for Lifting Rocks, Pulling Stumps, Building Wall, and the like; and I do hereby declare that the following is a full and exact description thereof.

My invention relates to the construction of the truss-work or supporting-frame of the machine. The general construction and arrangement of the machine is similar to that described in the patent to George W. Packer, dated August 29, 1865; there being four wheels and a connecting truss-frame adapted to lifting and supporting the rock or stump, and allowing it to be swung and turned at proper elevation between the two pairs of wheels.

Confining attention entirely to the truss, I will proceed to describe what I consider the best means of carrying out my invention, reference being had to the accompanying drawings, which form a part of this specification.

Figure 1 is a side elevation.

Figure 2 an end elevation, and

Figure 3 a plan view of my machine.

Similar letters of reference indicate like parts in all the figures.

A A B B represent the inclined timbers, which form the triangular framing. The timber A rests on the forward axle, or rather on the bolster C, which is supported thereon. The timbers B B rest near the ends of the rear axle, and the three are united firmly at the apex of the triangular pyramid thus formed. On each side of the timber A are fixed cheeks or stout pieces, as indicated by a, the function of which will presently appear. D D are straight or slightly-curved timbers, notched into the inclined timbers B B, into the cheeks a a, and firmly bolted thereto by bolts b, as indicated. E F are uprights, which support the extreme ends of the horizontal timbers D, and connect them to their respective supports. G G are holding-down bolts, arranged to cross each other, as represented, and to hold down the forward ends of the timbers D D. They are provided with adjusting-nuts g, and their tension may be regulated to compensate for any looseness or shrinking of the work. H H are holding-down bolts, which connect the rear ends of the timbers B B with the support or rear axle. I and J are inclined braces, of round iron or other suitable material, adapted to bear great tensile strain. They stand in inclined positions, as represented; the inclined braces I connecting the front bolster C to the timbers, at a point a little in the rear of the cheeks a, and the inclined braces J connecting the rear axle with the timbers D, a little forward of the inclined timbers B. These are provided with adjusting-nuts, and their tension may be graduated as required to support the mechanism and give strength and stiffness to the structure.

When my machine is subjected to a severe strain, in lifting and carrying a heavy rock or other object, the load is thrown upon the apex of the triangular frame A B B, and the tendency of the lower portion of the framing to be extended horizontally is resisted by the beams D and their attachments. The peculiar arrangement of the material allows the employment of a straight or nearly straight timber, D, while the base of the triangular frame is effectually held against spreading by the uprights E F, the holding-down bolts G H, and the inclined braces I and J. The arrangement has been tested, and found to operate successfully with heavy loads, while it allows a larger stump, rock, or other object to be swung and turned, and also allows the fore wheels of the machine to run under the truss-work, so as to allow the machine to be turned around in a manner which would not be possible without the base of the triangular framing connected by straight ties.

The curved ties described in the patent of George W. Packer, before referred to, are successful in practice, but are difficult to obtain in like localities. The timber required is too large and stiff to be prepared in the curved form, by artificial means, without great expense, and it is, in some situations, impossible to procure timber naturally so curved. My invention avoids these difficulties.

The machine is liable to be subjected to very severe transverse as well as vertical strains. There are periods when the whole force of a powerful team is expended in pulling sidewise on the tongue and front axle of the machine. This subjects the entire framing to a severe twisting or racking strain. The diagonal position of the front holding-down bolts G G greatly strengthens the front portion of the truss-work to resist such strain, without very materially increasing the weight or cost of the parts.

I believe it also very highly conducive to the rigidity of the structure, and its ability to resist such torsional or racking strain, to enlarge the horizontal timbers D D, enlarge the pyramidal framework A B B, and to bolt these parts firmly together, by making tie-rods, bolts, or braces G G H H I I J J so that their length may be adjusted by nuts or equivalent means. I am able to so proportion the length that but very little strain is thrown on the fastenings, between the horizontal timbers and the triangular framework, in supporting the load. Consequently there is but little transverse strain thrown on the inclined timbers A B B. In fact the fastening of D to the parts B B, and to the part A, as described, performs the double function of stiffening the machine laterally, and the steadyng or supporting the pyramidal framing against displacements, when strained with a heavy load.

Having now fully described my invention, what I claim as new, and desire to secure by Letters Patent, is as follows:

1. I claim the within-described novel construction of truss for a wall-building machine, the same consisting in the pyramidal framing A B B, the horizontal timbers D D, uprights E F, holding-down bolts G J, and inclined braces I H, combined and arranged substantially as and for the purpose herein set forth.
2. I claim, in such truss, firmly securing the timbers D D to the pyramidal framing A B B, by enlarging and bolting, or equivalent fastenings, at the points of contact, in addition to the truss-work before described, substantially as and for the purpose herein specified.
3. I claim the diagonal arrangement of the holding-down bolts G at the front of my truss, the same being arranged relatively to the timbers D, triangular frame A B B, and their several connections, substantially in the manner and for the purpose herein set forth.

In testimony whereof, I have hereunto set my hand in the presence of two subscribing witnesses.

THOS. S. GREENMAN.
